RADIO RECEIVING SYSTEM FOR VEHICLES

George P. Adair, Takoma Park, Md.

Application April 27, 1934, Serial No. 722,767

6 Claims. (Cl. 250—14)

My invention relates broadly to radio apparatus installations for vehicles of the internal combustion engine type and more particularly to an improved method and arrangement of signaling system having means for guarding the signaling apparatus against interference from the internal combustion engine ignition system while avoiding reduction of engine efficiency when the signaling apparatus is not in operation.

10 The principal object of my invention is to provide a method of improving engine efficiency in radio apparatus equipped vehicles in which the internal combustion engine ignition circuit is equipped with oscillation prevention means known as "suppressors", "resistors", "choke coils", or "reactance devices".

Another object of my invention is to provide a circuit arrangement for the ignition system of an internal combustion engine in radio apparatus equipped vehicles having means for guarding the radio apparatus against interference due to the operation of the ignition system while avoiding reduction in engine efficiency when the radio apparatus is not in operation.

25 Still another object of my invention is to provide an arrangement of ignition system for radio apparatus equipped motor vehicles in which oscillation suppressing devices are inserted in the distribution circuit of the ignition system when the signaling apparatus is in use and effectively removed from the circuit when the signaling apparatus is not in use.

A further object of my invention is to provide an electrically operative system functioning to 35 shunt the oscillation suppressors of an ignition system when the radio signaling apparatus on the vehicle is cut off from operation and operative to remove the shunts from the oscillation suppressors when the signaling apparatus is re-40 stored to operation.

A still further object of my invention is to provide a construction of gear adapted to be mounted on the head of an internal engine for guiding a multiplicity of control members in position 45 for actuating shunt switches adjacent the oscillation suppressors of the spark plugs and distributor head of an internal combustion engine, with means carried by said gear and coacting with the power control switch of the signaling 50 apparatus carried by the vehicle to effect a short-circuiting of the oscillation suppressors when the signaling apparatus is not in operation, while removing the short circuit from the oscillation suppressors when the signaling apparatus 55 is in operation.

Another object of my invention is to provide a mechanical arrangement operative in accordance with the on and off position of the power control switch of a signal receiving apparatus for effectively shunting or unshunting oscillation suppressors in the ignition system distribution circuit for guarding the signaling apparatus against the effects of ignition noises when the signaling apparatus is placed in operation while eliminating the effects of the oscillation suppressors from the ignition distribution circuit when the signaling apparatus is not in operation.

10 Still another object of my invention is to provide a construction of device attachable to spark plugs or distributor head of an internal combustion engine for suppressing oscillations in the ignition distribution circuit with spring actuated means for normally rendering said devices ineffective and operative to render the devices effective for suppressing oscillations in the ignition distribution circuit depending upon the off and on position of the power control switch of the signaling apparatus.

15 A further object of my invention is to provide a mechanism readily attachable to the head of an internal combustion engine and adjustable to provide guides for insulated control cords operative to open or close contacts across suppressor elements interposed in the distribution circuit of the ignition system of an internal combustion engine.

20 A still further object of my invention is to provide a construction of mounting device attachable to the head of an internal combustion engine and carrying a plurality of pulley devices shiftable to selected position in alignment with contact systems disposed adjacent oscillation suppressor elements adjacent the spark plugs of an internal combustion engine for guiding cords operative by movement of a two-position device in 25 accordance with the on and off movement of a power control switch of a signaling apparatus carried by a motor vehicle to render the oscillation suppressing means effective when the switch is moved to on position and ineffective when the switch is moved to off position.

25 Other and further objects of my invention reside in the method, circuit arrangement, and construction of oscillation suppression system for motor vehicles, as set forth more fully in the 30 specification hereinafter following by reference to the accompanying drawings, in which:

Figure 1 schematically and diagrammatically illustrates the ignition system of a motor vehicle and shows the cooperative relation of the control 35

switch of a signaling apparatus carried by a motor vehicle with the means for controlling the oscillation suppression means in the distribution circuit of the ignition system of the internal combustion engine on the vehicle, the radio apparatus power control switch being shown in "off" position; Fig. 2 is a fragmentary view showing the position of the control mechanism when the radio apparatus power control switch is moved to "on" position; Fig. 3 is a fragmentary view showing a modified circuit arrangement for the control mechanism; Fig. 4 is a cross-sectional view taken through one of the supporting devices attachable to the spark plugs showing the mounting means for the oscillation suppressors and illustrating the shunting switch of my invention; Fig. 5 is a lateral cross-sectional view taken on line 5—5 of Fig. 4; Fig. 6 is a vertical sectional view taken on line 6—6 of Fig. 4; Fig. 7 is a plan view partially broken away and shown in cross-section and elevation showing one arrangement of control gear which I may employ for controlling the position of the contactors in the ignition distribution circuit of the internal combustion engine; Fig. 8 is a side elevation of the gear shown in Fig. 7 partially broken away and shown in section for illustrating the arrangement of the adjusting means aligned with the contactors on the oscillation suppressors; Fig. 9 is a cross-sectional view on an enlarged scale taken through the gear shown in Fig. 8; Fig. 10 is an enlarged side elevational view showing one of the guide members employed for directing the control cord to the contact system adjacent the suppressor connected with the spark plug; Fig. 11 is a cross-sectional view taken through the gear of Figs. 7 and 8 and showing the position of the guide pulley which directs the control cord to the contact system on the oscillation suppressor at the distributor head of the engine; Figs. 12 and 13 show one form of contact device which I may employ for shunting the oscillation suppressor carried by the distributor head; and Fig. 14 illustrates a form of toggle switch which may be employed for controlling the power switch to the signaling apparatus while mechanically controlling the contact systems arranged to shunt the oscillation suppressors in the distribution circuit of the ignition system of the vehicle.

I have shown the system of my invention particularly adapted for automobiles but I desire that it be understood that the system of my invention may be employed in aircraft and in any internal combustion engine installation in which oscillation suppression means are employed in the distribution circuit of the ignition system.

My invention meets a considerable demand in automobile radio receiver installations for avoiding the detrimental effects of the oscillation suppressors in the distribution circuit of an ignition system. The interposition of resistors in the distribution circuit of an ignition system tends to reduce the size of the spark discharge in the internal combustion engine cylinders thereby impairing the operation of the engine. Additional drain is also imposed on the storage battery. Where the ignition system may be in somewhat bad condition in used cars, the addition of a radio receiver to such car with accompanying oscillation suppressors, tends to render the operation of the automobile more uncertain, particularly in starting.

My invention provides means for eliminating the oscillation suppressors from the distribution circuit of the ignition system at all times except

when the signaling apparatus is actually in use. Such signaling apparatus may normally not be cut into use until after the motor vehicle is in operation so that the rendering of the oscillation suppression means effective at that time does not tend to impair the operation of the engine. My invention enables maximum efficiency to be obtained from the internal combustion engine while permitting adequate operation of the signaling apparatus on the motor vehicle.

Referring to the drawings in more detail, the signal receiving apparatus installed on the motor vehicle is represented generally as including electron tubes 1, 2, 3, 4, 5 and 6 which may be connected in any preferred manner with a similar receiving circuit including an antenna system 7 and the chassis of the vehicle representing the ground indicated at 8. Any approved circuit arrangement may be employed for the signal receiving apparatus. I have indicated the heating circuit for the cathodes of the several electron tubes by reference character 9 connected at one side to ground 8 and at the other side to contact 10 of the power control switch 11. The power control switch 11 is movable to either of two positions with respect to contacts 10 and 12. In position on contact 10, the power control switch 11 provides a closed circuit from the storage battery system 14 through armature 15 to the power supply circuits of the signal receiving apparatus. The plate circuits of the several electron tubes are energized through any approved form of plate supply system indicated generally at 16 when power is supplied from the source 14 when the power control switch 11 is moved to contact 10. The output of the plate supply system is indicated at 17 connected to the several plate electrodes of the tubes constituting the receiving circuit. The plate supply system may be of the type which includes a vibrator controlling the connection of the potential source to a transformer system which connects to a filter circuit from which energy is supplied to the plate electrodes of the several tubes. I may employ a dynamotor system or any other standard system, for supplying the plate circuits or I may provide a plate battery in which event, the plate circuit would not be opened when the receiving set is turned off and only the heating circuit for the cathodes would be deenergized. The energy for exciting the field winding of the electrodynamic speaker is also obtained from the power source 14 when switch 11 is moved to contact 10 by reason of the circuit connection shown which leads through the winding 18 constituting the speaker field. A dial light 19 is also placed in operation upon movement of the power control switch to contact 10. A connection is taken from the power supply circuit of the radio receiver, as represented at 20 to provide excitation for an electromagnetic control system under a selected condition when the power control switch 11 is moved to contact 10, as will be more fully explained hereinafter. The electromagnetic control system may assume many forms. The form of the device illustrated is schematic and is only one example of many different structures which I may employ. As illustrated, the device comprises separate electromagnetic systems comprising pole pieces 21 and 22 disposed on opposite sides of the movable armature 24 which is pivoted at 25. The armature 24 has an extension arm 26 thereon which is normally maintained under tension by means of spring 27 to provide a toggle effect by which the armature is maintained in the position to which it is shifted upon the ini-

tial supply of power to a selected electromagnetic winding. The position of the electromagnetic device for the off position of the power control switch 11 has been illustrated in Fig. 1. The reverse position of the electromagnetic device for the on position of the power control switch is illustrated in Fig. 2. Pole pieces 21 and 22 are provided with separate electromagnetic windings designated at 28 and 29. Adjacent ends of these windings are connected together and grounded as at 8. The remote ends of the windings are connected through contact devices located adjacent the opposite ends of the movable armature of the electromagnetic device with the "on" contact 10 and the "off" contact 12 of the power control switch respectively. These contact devices are placed in the path of the movable armature and may be directly controlled thereby. Contact device 30 is located adjacent the end portion 24a of armature 24. A spring 30a tends to normally separate contacts 30, but the action of this spring is overcome by abutment of end portion 24a of the armature 24 effecting a closing of the contacts 30 completing the circuit through lead 20 from the power source through winding 28 to ground 8 thereby passing energy from source 14 through winding 28. It will be observed that movable armature 24 is connected to the insulated pull cable 37 which is guided over pulleys 38 to each of the contact devices 41, 42, 43, 44, 45 and 46 which shunt the oscillation suppressors 31, 32, 33, 34, 35 and 36 connected in the distribution circuit of the ignition system between spark plugs 51, 52, 53, 54, 55 and 56 and the contacts of the distributor head represented at 39. It will be understood that the pull cable 37 includes a multiplicity of individual cables which lead to the several contact devices over the several guide pulleys as shown. The distributor arm has been shown generally at 40 connected through driving member 47 with the operating cam 48 which controls the contact maker and breaker 49 connected to the primary circuit of the ignition induction coil 50, as shown. There is a contact device 57 provided in shunt relation to the oscillation suppressor 58 in circuit with the distributor arm 40 and with the secondary of the ignition transformer 50, as illustrated, and this contact device 57 is controlled by one of the cables which connects with the group of cables 37 and is guided over the pulleys 38. As pointed out hereinbefore, Fig. 1 illustrates the position of armature 24 for the off position of the power control switch 11 so that the several contact devices 41, 42, 43, 44, 45 and 46 are all shown in shunt position effectively eliminating the oscillation suppressors 31, 32, 33, 34, 35 and 36 from the ignition distribution circuit. When the power control switch 11 is moved to on position on contact 10, a circuit is completed from source 14 through switch arm 11, contact 10, conductor 20, contacts 30, winding 28, leading through ground 8, which results in the shift of armature 24 to an opposite position as a result of which, contacts 30 are open and contacts 59 are closed by the abutment of the end 24b of armature 24 with one of the spring members carrying contacts 59. Contacts 59 are closed against the action of spring 59a thus preparing the toggle switch for the next successive shifting operation when power control switch 11 is to be restored to off position on contact 12.

Figure 2 shows the effect of the shift of armature 24. Cable 37 is drawn over rollers 38 thus opening the contact systems which shunt the oscillation suppressors and effectively including the oscillation suppressors in the ignition distribution circuit so long as the signal receiving apparatus is functioning. It will be observed that the effects of sparking at contacts 30 and 59 are avoided by the inclusion of shunt paths around the contact systems. Condenser 60 and resistor 61 are connected in series and disposed in shunt with contacts 30. Condenser 62 and resistor 63 are connected in series and disposed in shunt with contacts 59. Condenser 64 is connected in shunt with the contact device 49.

The generator system for the motor vehicle is indicated generally at 65 which connects through automatic control relay 66 for controlling the charging of battery 14 through contact system 67. Suitable condenser 68 is connected across contact 67. The lead 69 extends to the light circuit and other power circuits on the motor vehicle. A suitable condenser 110 is connected across the generator 65 to suppress commutator sparking with inherent interference with the operation of the receiving apparatus.

As illustrated in Fig. 3, I may control the power circuit by a four-position toggle switch 70 which may be moved to contact 71 to energize electromagnetic winding 28 for shifting armature 24 in a position to open the contact shunts across the oscillation suppressors. This serves to precondition the ignition system by cutting the oscillation suppression means into the ignition system preparatory to the turning on of the radio set. The cutting on of the radio set is accomplished by moving switch 70 to contact 72 which cuts on the cathode circuit of the electron tubes, represented generally at 5, and also the plate circuit of the electron tubes as well as the field circuit of the electrodynamic speaker. With this arrangement, it is unnecessary for the electromagnetic control device to be continuously energized and, accordingly, a certain amount of drain is removed from the battery system. When it is desired to cut off the power circuit to the radio receiving set and restore the distribution circuit of the ignition system to a condition of maximum efficiency, toggle switch 70 is shifted to contact 73 thereby energizing winding 29 causing a shift of armature and the shunting of the contacts across the oscillation suppressors. The toggle switch 70 may be at once moved to off position 74 and yet the armature 24 will remain in its selected position without consumption of energy in the windings of the electromagnetic control device.

The structure of the shunting means for the oscillation suppressors may assume many forms and the forms of my invention illustrated, are for illustrative purposes. For example, in Fig. 4, I have shown spark plug 51 having the usual knurled nut terminal 75 adapted to engage the bracket carrier 76 connected to one end of the oscillation suppressor 31. I have shown the standard form of molded casing type of suppressor to which the contact system of my invention is applied, but it will be understood that other forms may be provided and the contact system molded as a part of the unit. A terminal bushing 77 projects from the opposite end of the suppressor 31 and is provided with an annular groove 78 adapted to receive the open lug end 79, shown in dotted lines, of the ignition distribution lead which is removed from the terminal 75 of the spark plug. If the conductor is of the type having an end resilient socket, it is engaged over the bushing 77 on the end of 75

Figure 2 shows the effect of the shift of armature 24. Cable 37 is drawn over rollers 38 thus opening the contact systems which shunt the os-

the suppressor, as shown in full lines, or if the closed end lug type of connector is used, it may be clamped under a screw-threaded bushing 77 in the same manner as previously held by terminal 75 on the spark plug.

A pair of upwardly extending members 80 and 81 are mounted on the suppressor and serve as mechanical supports and electrical connections for the opposite terminals of the contact device shown at 82. The resistor 31 has terminal heads 76 and 77 which are extended through members 80 and 81 to form a continuation of the circuit from the opposite sides of the resistor in series with the ignition distribution circuit and completing the circuit to the spark plug through screw terminal 75. The member 81 may carry contact element 84 thereon aligned with a movable contact element 82, carried by rod member 86 which passes through aligned apertures 86a in member 80. Rod member 86 carries collar 86a against which coil spring 87 is continuously effective to force movable contact 82 into electrical connection with fixed contact 84. The rod member 86 is provided with an eyelet or hooked end 86b through which insulated pull cable 37 passes. The position of shoulder 86a on rod 86 is such that positive connection between movable contact 82 and fixed contact 84 is assured at all times until pull cable 37 is operated to separate the contacts against the action of coil spring 87. A removable cover member 88 serves to protect the moving parts of the device from oil and dirt.

Figs. 7 and 8 show the schematic arrangement of the gear of my invention with respect to the head of an internal combustion engine which is represented schematically at 89. The spark plugs have been shown generally at 51, 52, 53, 54, 55 and 56 each provided with a mounting device 40 for the oscillation suppressor and contact system. The oscillation suppressors are shown at 31, 32, 33, 34, 35 and 36. The contact systems are arranged beneath the suppressors according to the structure shown in Figs. 4, 5 and 6. The gear comprises the horizontally extending member 90 which is open at one side and provided with jaw members directed toward each other providing guide rails 90a and 90b between which the plate members 91 may be adjusted to selected positions. Each of the plate members 91 is provided with journals on which pulley wheels 38 are mounted and around which the pull cables 37 are guided. The electromagnetic control relay is mounted in a housing 92 which forms a continuation of the horizontally extending member 90. The electromagnetic control mechanism has been indicated generally in dotted lines which show the magnetic devices 21 and 22 adapted to control the movable armature 24 for effecting an opening or closing of the shunts around the oscillation suppressors. The casing 92 which houses the electromagnetic control mechanism is suitably supported on the rear of the dash, as indicated generally in Figs. 7 and 8. Bracket members 94 may be provided for supporting the horizontally extending member 90 with respect to the head of the engine. When the pulley members 38 have been adjusted to selected positions aligned with the several contact devices adjacent the spark plugs, the metal forming the jaws 90a and 90b is pinched, as represented generally at 95 for locking the pulley members in selected positions. The distributor head is generally out of alignment with the several spark plugs and for this purpose, I may pro-

vide an angularly disposed supporting member for the guide pulley 38, as represented more fully at 96 in Fig. 11 so that the pull cable 37 is properly directed and guided to the oscillation suppressor which is employed in the distributor head.

Figs. 12 and 13, show one form of mounting for the oscillation suppressor in the distributor head in which the oscillation suppressor 59 is disposed in circuit with the conductor 97 forming part of the distribution circuit of the ignition system. The suppressor 58 may be either of the tubular type having aligned connecting means at opposite ends thereof or it may be of the elbow type having a connector adapted to engage the recess in the distributor head. Contacts 57 are normally closed to shunt the resistor 58 but may be opened by operation of pull cord 37 to operate contacts 57 by slightly displacing spring member 98. The distributor head indicated generally at 99 receives a connector formed on the end of resistor 58, as represented at 100. The resistor 58 is shown molded into a casing through which the support 105 connected with one end of the resistor extends to mount spring member 98. The opposite end of the resistor has support 106 connected thereto. The support 106 and spring member 98 serve as carriers for contacts 57 which are normally closed but are capable of separation upon operation of pull cord 37. A removable cover 107 is provided for housing the contacts and the associated mechanism and serving as a protection against dirt and grease.

Where electromagnetic devices are employed, I may provide a connection for pull cable 37 directly to the operating arm 101 of a toggle switch 102 as illustrated in Fig. 14, which is operated by movement of arm 103 of the heater control rheostat 104. When the rheostat is in off position, the position of toggle arm 101 is such that pull cord 37 is released to shunt all of the contacts across the oscillation suppressors. When, however, the toggle arm 101 is moved to on position, pull cable 37 is moved to displace all of the contacts thereby opening the contacts and rendering the oscillation suppressors effective in the distribution circuit of the ignition system.

The switch contacts may be applied to existing constructions of suppressors with slight modification. In some constructions, I may mold the contact system into the same casing with the suppressor thereby reducing the size and cost of the device.

While I have described my invention in certain preferred embodiments, I desire that it be understood that modifications may be made and that I intend no limitations upon my invention other than are imposed by the scope of the appended claims.

What I claim as new and desire to secure by Letters Patent of the United States is as follows:

1. Means for guarding radio receiving apparatus against interference from motor vehicle ignition systems comprising, in combination, with an internal combustion engine ignition system including a multiplicity of spark plugs and an ignition distribution circuit, a frame structure, means for supporting said frame structure adjacent the spark plugs of the internal combustion engine, a movable actuator disposed adjacent one end of said frame structure, oscillation suppressing means in said distribution circuit and in series with certain of said spark plugs,

contact systems normally shunting said oscillation suppressing means, an adjustable guide carried by said frame structure in substantial alignment with each of the said contact systems, and 5 tension members passing over said adjustable guides and interconnecting the said contact systems with said movable actuator whereby said oscillation suppressing means may be effectively included in the distribution circuit for one position of said movable actuator and shunted out of said ignition distribution circuit for another position of said movable actuator.

2. Means for guarding radio receiving apparatus against interference from motor vehicle 15 ignition systems comprising, in combination, with an internal combustion engine ignition system including a multiplicity of spark plugs and an ignition distribution circuit, a frame structure, means for supporting said frame structure 20 adjacent the spark plugs of the internal combustion engine, a movable actuator disposed adjacent one end of said frame structure, oscillation suppressing means in said distribution circuit and in series with certain of said spark plugs, contact systems 25 normally shunting said oscillation suppressing means, a multiplicity of adjustable carriers supported by said frame structure, a pulley member journaled on each of said adjustable carriers in substantial alignment with the oscillation suppressing means for said distribution circuit, and means interconnecting said 30 contact systems and passing around said pulley members and connected with said movable actuator whereby said oscillation suppressing means 35 may be effectively included in said ignition distribution circuit for one position of said actuator and may be shunted out of said ignition distribution circuit for another position of said movable actuator.

40 3. In a system for guarding radio receiving apparatus against the effects of ignition interference in motor vehicles, a frame structure supportable adjacent the spark plugs of a motor vehicle comprising a channel shaped member having a pair of coacting edges directed toward each other, a multiplicity of adjustable members adapted to be secured in selected positions along said channel shaped member and between said coacting edges, pulley devices carried by each of said adjustable members in substantial alignment with the spark plugs of the motor vehicle, oscillation suppressing means connected with certain of the spark plugs of the motor ve-

hicle, electrical shunting devices disposed in parallel with said oscillation suppressing means and flexible members passing over said pulleys and connected with each of said electrical shunting devices, said flexible members being controllable for effectively opening or closing said shunting devices with respect to said oscillation suppressing means.

4. Means for guarding radio receiving apparatus against interference from motor vehicle 10 ignition systems, comprising in combination, with an internal combustion engine ignition system including a multiplicity of spark plugs and an ignition distribution circuit, a frame structure, means for supporting said frame structure adjacent the spark plugs of the internal combustion engine, a movable actuator disposed adjacent one end of said frame structure, oscillation suppressing means in said distribution circuit and in series with certain of said spark plugs, contact systems 20 normally shunting said oscillation suppressing means, and a tension member connected with said movable actuator and having branch portions connected with said contact systems for effecting control of said contact systems by said 25 movable actuator.

5. Means for guarding radio receiving apparatus against interference from motor vehicle ignition systems, comprising in combination, with an internal combustion engine ignition system 30 including a multiplicity of spark plugs and an ignition distribution circuit, a frame structure, means for supporting said frame structure adjacent the spark plugs of the internal combustion engine, a movable actuator disposed adjacent one end of said frame structure, oscillation suppressing means in said distribution circuit and in series with certain of said spark plugs, contact systems 35 normally shunting said oscillation suppressing means, a guide carried by said frame structure in substantial alignment with each of said contact systems, and a tension member connected with said movable actuator and having branch portions adapted to pass over said guides and connected with said contact systems for effecting control of said contact systems by said 40 movable actuator.

6. Apparatus of the type described in claim 2 and wherein certain of said pulley members are mounted on axes disposed in one plane, and 50 another of said pulley members is mounted on an axis inclined with respect to said plane.

GEORGE P. ADAIR.
